UNITED STATES PATENT OFFICE.

OSCAR MCGRUDER COX, OF PLAINVIEW, TEXAS.

TRACTION-ENGINE.

1,099,538.

Specification of Letters Patent.

Patented June 9, 1914.

Application filed May 27, 1910. Serial No. 563,612.

To all whom it may concern:

Be it known that I, OSCAR MCGEUDER Cox, citizen of the United States, residing at Plainview, in the county of Hale and State of Texas, have invented a new and useful Traction-Engine, of which the following is a specification.

This invention relates to improvements in traction engines and the primary object of the invention is to provide means whereby the power of the driving cylinder may be applied directly to the axle of the traction wheel without affecting the ease with which the machine may be steered and without liability of bending or breaking the axle when the machine is being driven around short curves.

A further object of the invention is to arrange the operating mechanism in a compact form so that no unnecessary space will be occupied by the same and the dead weight of the machine will be reduced.

A further object of the invention is to improve and simplify the operating mechanism whereby it may be readily controlled by the engineer so that the engines may be driven forward or backward and the direction of travel reversed quickly and without unnecessary wear upon any of the parts.

A further object of the invention is to provide simple and efficient means by which the machine may be held against traveling and the power utilized to operate a threshing machine or other mechanism.

All the stated objects, and such other objects as will hereinafter incidentally appear, are attained in the use of the mechanism illustrated in the accompanying drawings and the invention consists in certain novel features of the same which will be herein-after first fully described and then more specifically pointed out in the appended claims.

In the drawings,—Figure 1 is a side elevation of a traction engine embodying my improvements. Fig. 2 is a plan view of the same with the boiler removed. Fig. 3 is a vertical section taken on the line 3—3 of Fig. 2. Fig. 4 is a detail side elevation of the reversing mechanism. Fig. 5 is a detail sectional view taken on the line 5—5 of Fig. 4. Fig. 6 is a detail elevation illustrating the manner of supporting the apparatus so that its power may be utilized for driving machinery. Fig. 7 is a fragmentary vertical cross section taken somewhat to the rear

of that of Fig. 3 and looking in the opposite direction.

In carrying out my invention, I employ a supporting frame consisting of longitudinal side beams 1 and cross beams 2 connecting the same, and intermediate longitudinal beams 3 extending beyond the cross beams 2 at their rear ends where they are connected by a supplemental cross beam 4. Diagonally disposed beams 5 connect the ends of the beams 4 with the rearmost beams 2, and additional longitudinal beams 6 extend between the cross beams 2 adjacent the side beams 1, as shown most clearly in Fig. 2. To the foremost cross beam 2, I secure a reach 7 in the front end of which is mounted a king bolt 8 upon which the steering axle 9 is mounted and adapted to oscillate. Guiding wheels 10 are mounted on the ends of the axle 9 and are provided with central annular ribs 11 adapted to take into the ground and thereby positively guide the apparatus in the desired line of travel. In order to turn the axle 9 about the king bolt 8, I secure to the axle, near the opposite ends of the same, chains or cables 12 which extend rearward therefrom so as to cross, as shown in Fig. 2, and are secured to and wrapped around a windlass or shaft 13 in opposite directions. This windlass 13 is mounted in suitable bearings 14 on the front cross bar 2, and is provided near its outer end with a worm pinion 15 with which meshes a worm 16 on the front end of a steering rod 17 extending back to the cab or engineer's platform and equipped with a hand wheel 18 by means of which it may be manipulated. It will be readily understood that when the steering rod or shaft 17 is rotated, the windlass 13 will be likewise rotated and one chain 12 will be wound on the windlass 13 and the other chain 12 will be unwound therefrom so that a pull will be applied to one end of the steering axle 9, and the said axle consequently caused to turn about the king bolt 8 and bring the steering wheels 10 into the desired line of travel.

The traction wheels 19 are rigidly secured to independent axles or driving shafts 20, each of which is journaled in suitable bearings on a side beam 1, the beam 6 parallel therewith, and the inner longitudinal beam 3. The axles are arranged in the same transverse line of the machine and are duplicates so that a description of one will ap-

ply to both. The axle is provided between the beams 3 and 6 with a pair of cranks 21, arranged at different angles to the shaft so that in the operation of the machine both 5 cranks will never be on a dead center and, consequently, no portion of the power applied to the cranks will be wasted in overcoming a dead center. To each of the cranks is pivotally connected the outer end 10 of a connecting rod or link 22 having its forward end pivoted to a cross head 23 which is secured rigidly to the rear end of a piston rod 24 extending from an engine cylinder 25 and operated by a piston within 15 the said cylinder, as will be readily understood. It will be observed that two engine cylinders are provided for each axle, and these cylinders are arranged one above the other, as shown most clearly in Fig. 3 and 20 are, of course, disposed at such an angle to each other as will bring both of them into planes radiating from the center of the crank shaft or axle. In this manner, the working cylinders will be so disposed as 25 to apply the power directly to the crank shaft. The front transverse beam 2 is not secured directly to the front ends of the longitudinal beams 1 and 3, but is connected therewith through intermediate short standards or braces 26. Lower beams 27 extend 30 from the braces 26 to the crank axle, and the rear ends of these beams 27 are secured to the side beams 1 and the inner beams 3 through suitable connecting bolts which also 35 serve to secure the bearings for the crank shaft between the said longitudinal beams. It will be observed, more particularly upon reference to Fig. 3, that a beam 27 is provided under each beam 1 and each beam 40 3 as well as under an intermediate longitudinal beam 28, the front end of the said beam 28 being connected with the front end of the side beam 1 by a cross bar 29 in order to impart the necessary rigidity to the structure. The beams 3 and 28 together with the innermost beams 27 constitute a guide or 45 way for the lower cross head 23, as will be readily understood from Fig. 3. The guide for the upper cross head 23, and the support 50 for the same, and the cylinder 25 from which the said cross head is operated, are furnished in part by the beam 6 and a supplemental beam 30 arranged directly under the beam 6 and secured thereto by suitable 55 bolts or similar fastenings at a point in rear of the rear limit of movement of the cross head. The beams 6 and 30 support the outer side of the upper cross head, and to support the inner side of the said cross 60 head, I provide beams 31 arranged parallel with the beam 6 and supported with the beam 6 from the longitudinal beam 3 by an arched connection 33 arranged at an intermediate point of the lengths of the beams 65 6 and 3 and arched sufficiently to clear the

connecting rods 22 in all phases of their movement. A lower beam 32 is provided directly under the beam 31 so as to complete the guide and support for the upper cross head, and this beam 32 is bolted to the beam 31 or otherwise secured so as to be supported rigidly in its proper position without interfering with the movement of either cross head or either connecting rod. The exact detail connection and arrangement of the 70 several beams are illustrated only generally in the drawings, inasmuch as they are mere matters of mechanical detail which do not affect the operation or scope of my invention. 75

The steam chest 34 for the upper cylinder is arranged at the outer side of the same, while the chest 35 for the lower cylinder is arranged at the inner side of the same. Projecting from each steam chest is a valve 80 stem 36 arranged to reciprocate in a guide 37 mounted on the supporting frame, and connected with the outer end of the said valve stem is a link 38 having its rear end pivoted to a slide 39 mounted within a 85 grooved arcuate guide plate 40 which is pivoted at its center to a suitable supporting block 41 on the main frame. On the rear edge of this guide plate 40, near the upper end of the same, is pivoted the front end of 90 a pitman 42 having its rear end constructed with clamping jaws 43 adapted to embrace an eccentric 44 secured rigidly upon the crank shaft or axle. The valve stem projecting from the inner lower steam chest 35 95 is pivoted directly to the front end of the link 38, but the valve stem projecting from the upper steam chest is connected with the link 38 through an intermediate rock shaft 45 journaled in suitable bearings on the main frame and having a crank arm 46 near its inner end to which the valve stem is pivoted, and a crank arm 47 at its outer end to which the end of the link 38 is pivoted. An interposition of this rock shaft 45 is 100 necessary in order to permit the connections between the valve stem and the eccentric to clear the traction wheel 19, as will be 105 readily understood from Fig. 2.

It will be readily understood, from the description thus far given, that steam admitted through the steam chest to the working cylinder will act upon the piston in the said cylinder so as to reciprocate the cross head and thereby transmit motion through 110 the connecting rod directly to the crank on the driving shaft or traction wheel axle. Said axle will be rotated under the power thus applied thereto, and the eccentric 44 will, of course, be actuated and a reciprocating movement imparted to the pitman 42 which will be transmitted directly to the vibratory plate 40 so as to oscillate the same upon its pivot and thereby actuate the link 38 so as to reciprocate the valve stem and, 115 120 125 130

consequently, direct the steam from the chest alternately to opposite ends of the cylinder in the usual manner. The speed of the engine may be controlled by adjusting the slide 39 toward or from the pivot of the plate 40 and may be reversed by moving the said slide to the opposite side of the pivot of the said plate, as will be readily understood. In order to shift the slides for all the valves simultaneously, I pivotally secure to each slide a link 48 which extends upward therefrom to a crank arm 49 projecting rearwardly from a rock shaft 50 mounted in suitable bearings on the under side of the boiler 51 and provided with an upstanding crank arm 52 to which a connecting rod 53 is pivoted, the said connecting rod extending rearwardly to any convenient point adjacent the engineer's platform where it is pivoted to an operating lever 54 provided with a latch 55 adapted to engage the usual holding rack 56. It will thus be seen that by adjusting the controlling lever 54 the engineer may move the said slide 39 toward or from the pivot of the plate 40 so that the extent of movement around the said pivot imparted to the slide may be regulated and, consequently, the rapidity of movement of the steam valve adjusted as may be desired.

The boiler 51 is supported upon the main frame by standards 57 and 58 at the rear and front ends of the same, and upon the boiler, I provide the usual steam dome 59 from which a steam pipe 60 passes around the boiler to convey the actuating fluid to the steam chests. This steam pipe 60 is provided below the boiler with a branch 61 in which is mounted a suitable cut-off valve controlled by a speed governor 62 which is actuated through a belt 63 connecting the pulley 64 on the stem of the said valve with a driving pulley 65 on the inner end of one of the axles or crank shafts. From the lower end of the branch 61 smaller pipes 66 conduct the steam to the several steam chests, as will be understood most readily upon reference to Figs. 2 and 3. The exhaust pipes 67 from the chests on each side of the machine unite in a common conductor 68 which passes to and through a feed water heater 69 mounted on the side of the boiler, and after passing through the said heater enters the front end of the boiler and discharges through the smoke stack 70 so as to create a forced draft which will maintain the fire in the fire box at the rear end of the boiler in the desired state of efficiency. The feed water heater is connected in any desired manner with a tank or source of water supply which is not shown in the drawings, as it forms no part of my present invention. Any convenient form of throttle valve may be provided within the steam dome 59 and the throttle rod 71 of the said valve will pass rearward

to a controlling lever 72 provided at the rear end of the boiler within convenient reach of the engineer.

In order to transmit the power generated in the engine to drive a threshing machine or other apparatus, I provide on one of the crank shafts a band pulley 73 which is connected by a belt 74 with a pulley 75 on the inner end of a countershaft 76 mounted in suitable bearings on the under side of the boiler and equipped at its outer end with a fly wheel 77 which also serves as a band pulley around which a driving belt may be passed to impart motion to the machinery to be operated. In order to utilize the power of the engines to perform work in threshing or for other purposes, it is necessary to maintain the engine against traveling, and for this purpose I provide means for lifting the traction wheels from the ground so that the power exerted by the working cylinders will not cause the traction engine to travel. Upon the beams 8, in rear of the traction wheels I mount cylinders 78 in which are suitable pistons 90 having their piston rods 79 extending from the upper ends of the cylinders and pivoted, as at 80, to the said beams. A pipe 81 leads from the boiler to each of these cylinders 78 to admit steam to the lower end of the same below the piston thereof and the flow of steam through this pipe is controlled by a cut-off valve 82 which may be easily operated by the engineer. The cylinders are normally held in an elevated position by means of chains or cables 83 attached to the upper ends of the cylinders and extending upward therefrom to a holding lever 84 provided with a latch 85 adapted to engage a rack 86 of a well known form. When it is desired to lift the traction wheels from the ground, the lever 84 is moved downward so as to permit the cylinders to drop into the position shown in Fig. 6, after which the valve 82 is opened 110 so as to admit steam to the lower ends of the cylinders and force the pistons therein upward, as will be readily understood. As the said pistons rise, the rear end of the main frame will, of course, be moved upward and the entire apparatus will be then supported by the said cylinders 78 and the front steering wheels 10, as will be readily understood, the traction wheels being lifted clear of the ground so that their rotation 120 will not cause the traction engine to travel. In order to hold the frame in the elevated position, pawls 87 are pivoted upon the frame adjacent the cylinders and provided with a plurality of notches 88 in their edges adapted to engage the upper ends of the cylinders, as shown in Fig. 6, whereby the frame will be prevented from dropping when the flow of steam is cut off or the steam in the cylinders condenses. When the 130

engine is traveling, these pawls will be held in an inoperative position alongside the beams 3 to which they are pivoted by any convenient form of bracket or lug, as indicated at 89. The provision of a plurality of the notches 88 permits the engineer to lift the frame to a greater or less degree, as may be necessary under varying conditions, and will be found especially desirable where the ground is not firm, inasmuch as the preliminary sinking of the cylinders under the weight of the engine may be counteracted by admitting more steam to the cylinders, and consequently raising the pistons to a greater extent.

In order to obtain a firm footing in soft ground, I may connect the cylinders by a transverse foot or platform 90 which will furnish an extended bearing against the ground, as will be readily understood. The provision of these lifting cylinders will be found advantageous should the traction wheels drop into a hole in the road, as they may be readily utilized to remove the wheels from the depression without great delay in the travel of the machine.

It will be understood, of course, that when the machine is to be lifted so as to apply its power for threshing or similar purposes, the admission of steam to the working cylinders is arrested and steam is then admitted to the lifting cylinders while the driving elements are inactive. If, however, it be desired to carry the engine over some obstruction, which has temporarily arrested its travel, the lifting cylinders are lowered without cutting off the flow of steam to the working cylinders, and steam is then admitted to the lifting cylinders so that they will then act as levers to push the frame forward so that the force of the steam admitted to the lifting cylinders will be added to the power exerted by the working cylinders in rotating the traction wheels and, consequently, the obstruction will soon be passed.

It will be seen from the foregoing description that I have provided an exceedingly simple and compact arrangement of working parts by which the power generated in the working cylinders is transmitted directly to the axles of the traction wheels so that none of the power is lost through driving a long or complicated train of gearing. Furthermore, the space occupied by the gearing in all forms of traction engines known to me is saved by my invention, and the dead weight, which it was necessary for the engine to carry, is reduced. By providing a separate axle for each traction wheel I am enabled to apply the power directly to the axle or driving shaft without any liability of bending or breaking the same, when turning corners, inasmuch as the trac-

tion wheels are independent of each other, and the engines driving one wheel are independent of the engines driving the other wheel and, consequently, will automatically adapt themselves to the difference in the load placed upon the two wheels in turning the machine out of a straight line. The means for actuating the governor and the means for transmitting the power to a distant point are arranged below the boiler so that they will not in any way interfere with the movements of the engineer in cleaning or adjusting any of the parts and utilize space which has heretofore been unavailable. The valve gear devised by me and herein disclosed is exceedingly simple in its construction and direct in its operation.

The advantages of the construction and of the method of operation will be readily apparent to those skilled in the art to which the invention appertains, and while I have described the principle of operation of the invention, together with the apparatus which I now consider to be the best embodiment thereof, I desire to have it understood that the apparatus shown is merely illustrative, and that such changes may be made when desired as are within the scope of the claims appended hereto.

Having thus described my invention, what I claim is:

1. In a traction engine, the combination of a main frame, independent crank axles mounted therein, a traction wheel on each crank axle, a pair of engines connected directly with each crank axle, the engines of each pair being arranged one above the other, and means driven by each crank axle for controlling the admission of a working agent to the engines connected with said axle.

2. In a traction engine, the combination with a main frame, of a pair of crank axles mounted thereon, a traction wheel secured on each axle, engines connected directly with each axle, a band pulley on the inner end of each axle, and means for transmitting power from the said band pulleys.

3. In a traction engine, the combination of a frame, independent crank axles mounted therein, a traction wheel secured on each axle, engines connected directly with each axle, a counter-shaft on the frame, a band pulley on the inner end of one of the axles, and connections between the said pulley and the counter-shaft.

4. In a traction engine, the combination of a main frame, a pair of crank axles mounted thereon, a traction wheel secured to each axle, engines directly connected to each axle, a band pulley on the inner end of each axle, a governor common to the engines connected to box axles, connections between one of the band pulleys and the gov-

ernor, a counter-shaft on the frame, and connections between the other pulley and the counter-shaft.

5. In a traction engine, the combination with a frame and boiler, a pair of shafts mounted independently in the frame below the boiler and in transverse alinement, a traction wheel mounted on each shaft, a pair of cranks provided on each shaft, a 10 pair of engines at each side of the frame below the boiler, said engines being arranged one above the other and at an angle to each other and in planes radiating from the center of the crank shafts, the pistons of said 15 engines being separately and directly connected to the cranks of said shafts.

6. In a traction engine, the combination of a main frame, independent crank axles

mounted therein, a traction wheel on each crank axle, a pair of engines connected directly with each crank axle, the engines of each pair being arranged one above the other and at such an angle to each other as will bring both of them into planes radiating from the center of the crank axle, and 20 means driven by each crank axle for controlling the admission of a working agent to the engines connected with said axle.

25 In testimony that I claim the foregoing as my own, I have hereto affixed my signature in the presence of two witnesses.

OSCAR McGRUDER COX.
